UNITED STATES PATENT OFFICE.

GEORGE H. SEBRING, OF LEHIGHTON, PENNSYLVANIA.

RAILWAY-CAR TRUCK.

SPECIFICATION forming part of Letters Patent No. 650,594, dated May 29, 1900.

Application filed October 2, 1899. Serial No. 732,336. (No model.)

To all whom it may concern:

Be it known that I, GEORGE H. SEBRING, a citizen of the United States, residing at Lehighton, in the county of Carbon and State of 5 Pennsylvania, have invented new and useful Improvements in Railway-Car Trucks, of which the following is a specification.

My invention relates to improvements in railway-trucks.

It has for its objects, primarily, to provide for readily accommodating the movement of the car axles and wheels in their transit over the rails straight ahead, rounding curves, and passing over any inequalities or obstacles, 15 so as not to affect or strain the truck-frame or housings, and to suitably house or inclose the bearings or journals against displacement and yet permit them to readily yield laterally and longitudinally as necessary, and to provide 20 for the convenient oiling or lubricating of the parts, and to otherwise improve the structural features of the truck-frame and its adjunctive parts.

It consists of the combination and arrangement of parts, including their construction, substantially as hereinafter more fully disclosed, and specifically pointed out in the 25 claims.

In the accompanying drawings, illustrating the preferred embodiment of my invention, 30 Figure 1 is a view showing it applied for use in a truck. Fig. 2 is a vertical transverse section, and Fig. 3 is a horizontal section, both taken through one end portion or housing of 35 the truck-frame and journals or bearings. Fig. 4 is a detached broken perspective view of the housing or truck-frame. Fig. 5 is a similar view of an oil or lubricant cup or receptacle, and Fig. 6 is a vertical cross-section 40 of the same. Fig. 7 is a detail perspective of the journal-bearing boxes.

It will be understood that I do not limit myself to details as herein shown, as they may be varied or changed at will, according 45 to circumstances, without departing from the spirit of my invention and the same yet remain intact and be protected.

In carrying out my invention I provide, instead of the solid truck frame or bar, as heretofore, what may be very properly termed 50 "skeleton lateral supports" 1, 1, suitably as-

sembled and rigidly connected by a central connecting-bar 2, constituting the truck-frame. Each of the lateral supports in itself consists of a frame or skeleton work, as indicated, having end housings 1^a for the reception of the journals or bearings and oil or lubricant cups or boxes presently described, and intermediately of said housings said frame is subdivided horizontally by a binder-piece 55 or reinforce 1^b, affording a convenient support and attachment for the usual elliptic springs, upon which is secured the cross-bar or bolster, being bolted in the ordinary way to the car-body, none of said latter parts, however, being shown, as they constitute no part of my invention. Said lateral supports 1 are themselves connected together by a connecting-bar 2, as usual. These end housings 1^a 1^a are themselves open or frame work and inclose 60 or receive skeleton-like or open-work supplemental housings 3 and have lateral vertical flanges 1^c 1^c to prevent outward displacement of said supplemental housings, the latter playing freely vertically and horizontally between 65 vertical or upright members 1^d of said housings and guarded by said flanges, said frame, with its housings, being limited in the vertical yielding movement by the bottom and top horizontal cross pieces or members of said 70 housings.

The lower, preferably rotary, bearings or disks 4 have their axes journaled in bearings 4^a, arranged so as to be carried by the supplemental housings 3, the car-axles having 75 journals 5 resting upon or engaging said rotary bearings or disks 4. Suitably disposed within said housings are oil or lubricant receptacles or cups 6 to furnish lubricant or oil for the car-axle journals, as required, to lubricate the same, said axle-journals having lubricant-feeding disks 7, as usual, and hung above said journals are additional rotary bearings or disks 8 in contact therewith, affording antifrictional bearings therefor. Said 85 bearings or disks 8 have their journal-bearings in the under sides of boxes or blocks 8^a, carried by supplemental housings 3, said supplemental housings being cushioned above by springs 8^b, interposed between cross bars 90 or pieces 3^b, connecting opposite side pieces of said bearings and the tops of the housings 100.

1^a 1^a to properly hold the same yieldingly in place. The oil or lubricant receptacles or cups 6 each comprises, preferably, a semicircular bottom or cup portion proper, 6^a, with its upper 5 indent edges let into lateral grooves or gains 6^b of a top or cover 6^c, dished or concaved out upon its under side to conform to the car-axle journals, and at the end of said top or cover is a forwardly and rearwardly and upwardly 10 extending plate or flange 6^d, having a supply-opening 6^e through it for replenishing the supply of lubricant or oil in the oil cups or receptacles as required.

In view of the foregoing it will be seen that 15 the undue rigidity, as heretofore has existed between the truck-frame and the car-axles, is overcome by reason of the skeleton-like or open-work nature of the truck-frame and the freedom of play laterally and vertically permitted of the journal-bearings carried by the 20 housings of said truck-frame, thus readily accommodating or conforming to the movement of the car wheels and axles whether traveling in straight lines, rounding curves, 25 or contacting with unevennesses or obstacles, such as happens in railway travel, and thus prevent the straining of the truck-frame or otherwise injuriously affecting the same, as would otherwise be liable to occur.

30 Having thus fully described my invention,

what I claim, and desire to secure by Letters Patent, is—

1. A railway-car truck comprising the skeleton supports, the supplemental housings within said supports, the springs interposed between the supports and the housings, the axles extending through the housings, rollers journaled in said housings and bearing at different points against the axles, and the oil-cups suspended from the roller-bearings, substantially as described. 35

2. In a railway-car truck, the truck-frame comprising the skeleton-like or open-work lateral supports or frames having open-work end housings, inclosing oil or lubricant cups 45 or receptacles for the car-wheel axle-journals, having their bottoms formed with indent edges let into grooves or gains in the ends of a top or cover having an extended outer or front portion provided with an oil replenishing or supply opening, substantially as set forth. 50

In testimony whereof I have heretunto set my hand in presence of two subscribing witnesses.

GEORGE H. SEBRING.
